UNITED STATES PATENT OFFICE.

CLINTON S. COLGROVE, OF WINCHESTER, TENNESSEE.

SPRING-BED.

SPECIFICATION forming part of Letters Patent No. 254,277, dated February 28, 1882.

Application filed November 16, 1881. (No model.)

To all whom it may concern:

Be it known that I, CLINTON S. COLGROVE, of Winchester, in the county of Franklin and State of Tennessee, have invented a new and useful Improvement in Spring-Beds, of which the following is a full, clear, and exact description.

Reference is to be had to the accompanying drawings, forming part of this specification, in which similar letters of reference indicate corresponding parts in both the figures.

Figure 1 is a side elevation of my improved spring bed-bottom; and Fig. 2 is a plan view of the same, some of the slats being broken away to better show the construction.

The frame is composed of the end cross-bars, A A, at head and foot, side bars, B B, and the intermediate bars, C C, which are secured at their ends upon the upper side of the cross-bars A A, the side bars, B B, being secured to the under side of said cross-bars, as shown clearly in Fig. 1.

At the head of the frame the intermediate bars, C C, are formed with the notches e e, and to the outside of these bars are hinged the arms D D, which are provided with the hinged pawls or braces E E, the lower ends of which are adapted to engage in the notches e e of the intermediate bars for raising and supporting the head of the bed-bottom, as shown in the drawings. These pawls or braces are tied together by the cross-piece d for causing them to act together and as one pawl or brace.

Across the bars C C and the arms D D are placed the slats F F', upon which the coiled cone-springs G G' are placed. Between the ends of these slats F F' and the side bars, B B, are placed the series of side bottom springs,

H H', which support the ends of the slats. The series of coiled springs G G', after being secured upon the slats of the bed-bottom, are coupled together by the wires J J, which are bent to form a square, and to interlace with the upper wires of the coils in such manner that four coils are bound together by each of the wires J, as shown in Fig. 2. After the wires J have been placed around the wires of the coils the ends are united by twisting in the ordinary manner, thus making an effective, easily applied, cheap, and firm coupling, and by means of the hinged arms D D, pawls or braces E E, and the series of notches e e the head portion of the bed-bottom can be easily raised to any height or slant to suit the convenience of the occupant, or may be lowered on a level with the main portion of the bottom, as desired, thus rendering the bed-bottom very cheap and complete.

Having thus described my invention, I claim as new and desire to secure by Letters Patent—

In a bed-spring, the combination, with the end bars, A, the side bars, B, the intermediate bars, C, provided with notches e, the slats F, the spring G, secured to the upper surface of the said slats, and the springs H at their ends, of the arm D, hinged to the said intermediate bars and provided with the pawls E, the slats F', the springs G', secured to the upper surface of the slats, and the springs H' at their ends, substantially as and for the purpose set forth.

CLINTON S. COLGROVE.
